(57) **CLAIM**

The ornamental design for a display screen or portion thereof with graphical user interface, as shown and described.

DESCRIPTION

FIG. 1 is a front elevational view of a first embodiment of a display screen with graphical user interface;

FIG. 2 is a front elevational view of a second embodiment; and,

FIG. 3 is a front elevational view of a third embodiment. The features shown in even broken lines do not form part of the claimed design. The dot-dash lines illustrate boundaries of the display screen or portion thereof and do not form part of the claimed design.

1 Claim, 3 Drawing Sheets
